UNIVERSAL SCREW HEAD

Lawrence M. Curtiss, Mountainside, N.J., assignor to The Thomas & Betts Co., Elizabeth, N.J., a corporation of New Jersey

Filed July 2, 1964, Ser. No. 379,993

4 Claims. (Cl. 85—45)

The present invention relates to threaded fasteners generally and more particularly to a universal head for screws, bolts and the like of various kinds having a substantially flat "Fillister" like head portion with a cavity and cross slots recessed therein.

More specifically, the invention relates to screws generally which are provided with a cross slotted driving recess in the head thereof, whereby to selectively accommodate each of several conventional driving instrumentalities therein, the invention residing in the addition thereto of integral means for guiding or deflecting the working end of a winged driving tool into its recess, and a bladed tool into alignment with one or both of said slots in said screw head when brought into contacting relation therewith.

Prior art screw heads of this character while considered satisfactory in many applications possessed particular disadvantages in that considerable difficulty was often experienced in quickly aligning and inserting a single or crossbladed driving tool into one or both of a pair of intersecting slots in such screw heads particularly when the screws are part of small electrical fittings, for example, which fittings are often used in junction boxes and other close and/or difficult quarters where a clear and full sight approach to a set screw, for example, cannot be had. Thus, a screw head which avoids or greatly reduces such difficulties in the manipulation thereof is highly desirable and useful.

Accordingly, it is an object of the invention to provide an improved cross-slotted and/or axially recessed screw head which is adapted for automatically angularly deflecting a conventional driving tool into central alignment with either one or both of said cross slots when brought into contact with said screw head.

A further object of the invention is to provide an improved cross slotted and/or axially indented flat "Fillister" type screw head which is adapted to be readily engaged and actuated by either one of several conventional screw drivers of compatible size as for example, a single blade, cross blade, pointed, winged "Phillips" type, or a driving tool having a flat ended square shank.

Another object of the invention is to provide an improved cross slotted and/or axially recessed "Fillister" type screw head in the use of which an operator need only point a selected driving tool to the approximate center thereof and the tool moved into coactable contacting relation therewith, whereby the driving tool is automatically centered and oriented into alignment with and guided into either one or both of said cross slots and a recess in the intersection thereof.

With the above and other objects in view, the invention resides in the novel construction, combination, and arrangement of elements, the novel features of which are set forth with particularity in the appended claims, the invention itself, however, both as to the combination therein and method of operation together with additional objects and advantages thereof, being best understood from the following description of a specific embodiment thereof, when taken in connection with the accompanying drawing in which:

FIGURE 1 is a perspective view showing a Fillister type of screw head as provided with a pair of cross slots, a cavity formed in the slot intersection on the screw axis,

2

and a pair of oppositely inclined flat surfaces formed on each of the angularly spaced head portions formed by said intersecting slots in accordance with the invention;

FIGURE 2 is a top plan view of the same;

FIGURE 3 is a sectional view taken on the line 3—3 of FIGURE 2; and

FIGURE 4 is a similar sectional view illustrating a modification of the screw head in FIGURE 3.

Referring to the drawing, a screw head formed in accordance with the invention is indicated at 10 in which a pair of rectangular slots 12 and 14 are formed in intersecting relation and substantially at right angles on the screw axis. Both of the intersecting slots are identical, of the same depth, and both extending diametrically across the entire diameter of the screw head 10, which is straight and of substantially uniform diameter and of a length proportional to the threaded shank 16 of the screw after the manner of conventional flat head "Fillister" type machine screws. The side walls of the slots 12 and 14 are parallel respectively throughout their entire extent and are slightly inclined or diverge outwardly from the bottom thereof to their upper defining edge to readily receive tapered single blade screw drivers.

The bottom of the slots 12 and 14 are flat surfaces, all of which lie in the same surface of revolution except for a center clearance cavity or indentation 18. The center cavity 18 is in the form of an inverted cone with a rounded apex 20 located on the screw axis with the diameter at the top of the cavity slightly larger than the width of the slots as clearly shown in FIGURES 1 and 2.

It will be noted that the intersecting slots form a plurality of diametrically opposite, angularly spaced triangular head portions or segments 22 with their inner corner portions 24, disposed radially of the screw axis and projecting substantially over or into the cavity 18, whereby they are adapted for driving engagement with either of a plurality of different known driving tools.

In accordance with the invention, the top face or crown of each of the plurality of angularly spaced head portions or segments 22, is in the form of a compound angle by reason of the fact that its surface is inclined radially downwardly from its peripheral edge to its inner corner 24, located at or over the central cavity 20, and also inclined angularly or circumferentially in opposite directions downwardly to and terminating at its adjacent slot defining edge whereby a line or ridge 26, extending radially across the center of each of the segments 22, divides the same into two sloping triangular surfaces 28. Thus, the compound angle formed on the top face or crown of each of the head portions 22, provides the means whereby a driving instrumentality is deflected toward the center of the screw head 10, and into the cavity 18, and at the same time oriented into alignment with either or both of the intersecting slots 12 and 14, upon being brought into contacting engagement with the top face or crown of the segments 22.

While the cavity 18 on the axis of the screw head 10, as best shown in FIGURE 3, merely provides clearance for pointed, winged driving tools, similar winged driving tools having a blunt end require little or no clearance. Thus, to accommodate all kinds of winged type screw drivers, the bottom of the slots 12 and 14 may slope slightly downwardly toward the axis of the screw as at 30 and the depth thereof increased slightly whereby the clearance cavity 18 may be dispensed with as clearly shown in FIGURE 4.

While the screw head shown is of the machine type, the recessed head 10 is nevertheless adapted to be formed on other screws such as wood screws and on bolts, and even applied to the headless end of a common shaft or screw shaft.

Thus, when a driving tool of the conventional blade

type, cross blade type, pointed winged type, or the square shank type, is brought into contacting engagement with the screw head and not in the center thereof, the oppositely inclined top faces 28 of the segments 22, will deflect and orient the tool into the cavity 18, and into alignment with either or both of the intersecting slots 12 and 14. As aforesaid, the length of the screw head 10 and the diameter thereof is substantially of the "Fillister" type depending of course upon the size of the screw thread which, for the purpose of this invention, may vary from size 4 to 20, for example.

While the invention has been illustrated and described with respect to certain embodiments thereof, it is to be expressly understood that various changes and modifications may be made therein without departing from the inventive concept underlying the same. Therefore, the invention is not to be limited except as is necessitated by the prior art and the scope of the appended claims.

What is claimed is:

1. A screw head of substantial length and uniform diameter having a cross-slotted driving recess centrally thereof forming a plurality of diametrically opposite triangular segments, each of said segments presenting a slightly inclined upstanding corner edge radially of and adjacent the screw head axis adapted to be engaged by a winged type driving tool, each of said segments having a top face and a ridge extending radially of said screw

head and bisecting said segment, said top face being inclined downwardly radially toward the screw head axis and inclined downwardly in opposite directions from said ridge so as to define a pair of sloping triangular surfaces 5 the terminal edges of which define the cross-slots and which are adapted to deflect a bladed driving tool into alignment with the slots in said recess when brought into contacting engagement with said screw head.

2. A screw head as defined in claim 1 and further including a cavity formed in the slot intersection on the screw axis and extending below the bottoms of said slots.

3. A screw head as defined in claim 1 wherein the bottoms of said slots constitute flat surfaces throughout their length and are located in the same surface of revolution.

4. A screw head as defined in claim 1 and further including a substantially conical indentation formed in the slot intersection on the axis of the screw head and extending slightly below the intersecting bottoms of said slots.
